UNITED STATES PATENT OFFICE.

GABRIEL A. BOBRICK, OF BOSTON, MASSACHUSETTS.

ADJUSTABLE FURNITURE.

SPECIFICATION forming part of Letters Patent No. 605,806, dated June 7, 1898.

Application filed December 26, 1896. Serial No. 616,963. (No model.)

To all whom it may concern:

Be it known that I, GABRIEL A. BOBRICK, of Boston, county of Suffolk, State of Massachusetts, have invented an Improvement in Adjustable Furniture, of which the following description, in connection with the accompanying drawings, is a specification, like letters on the drawings representing like parts.

Adjustable furniture, and particularly school seats and desks, is now made in such manner as to be readily regulated to the size of the pupil, the desk or seat being mounted on two-part standards, one member of which is securely attached to the floor and the other member to the article of furniture. The two members of the standard have been made with their adjacent faces adapted to slide over each other in the direction of adjustment, a clamp on one member acting upon the portion of the other member between them to retain the standard in adjusted position, the intermediate member being wedge-shaped and tapering downward. It has been found in practice that such construction is open to the objection that when the pupil's knees are raised beneath a desk, as when crossing the legs, the upward pressure will tend to loosen the parts of the standards, no matter how tightly clamped in the first place.

As the wedge tapers downward, the slightest loosening of the clamp in the manner described destroys the adjustment and the desk becomes loose and will rattle. One of the objects of my present invention is to obviate this objectionable feature, while retaining all the valuable features of the adjustable support or standard, and I attain such object by reversing the direction of taper of the wedge portion, preventing upward movement of the parts when adjusted, displacement in the opposite direction being prevented by independent means.

Other features of my invention will be hereinafter described, and particularly pointed out in the claims.

Figure 1, in side elevation, represents a school-desk provided with standards embodying my invention. Fig. 2 is a vertical sectional view on the line $x x$, Fig. 1, the desk being shown in elevation and broken off. Fig. 3 is an enlarged transverse section through

the standard on the line $x x$, Fig. 1. Fig. 4 is an enlarged detail, partially in section, of a slightly-modified form of clamping and movable member; and Fig. 5 is a detail showing the position assumed by the clamping-bolt in old forms of construction when the clamp is loosened.

One member of the standard is shown as an upright preferably open casting a , adapted to be rigidly secured to the floor and having at or near its upper end a transverse portion or head a' ; provided with a suitable opening for the clamping-bolt d . A lug or shelf a^2 projects from the outer face of the head, beneath the bolt-opening, the bolt resting upon the shelf, as clearly shown in Figs. 2 and 4, for a purpose to be described.

The fixed member a has longitudinal bearing-surfaces a^3 , extended vertically or in the direction of adjustment, to support co-operating extended bearing-surfaces b^3 on the adjacent face of the movable member b , which member is securely attached to the desk or other article in suitable manner. The movable member b is longitudinally slotted at b' to receive the bolt d , and its outer face is inclined relatively to the bearing-surface b^3 , thus giving a wedge shape to the member, tapering toward its upper end.

I have herein shown the wedge form as attained by ribs b^2 , one at each side of the slot b' and of greatest height at the lower end, decreasing gradually therefrom to the upper end. The tops of the ribs are thus in a plane inclined to the vertical or to the bearings b^3 .

The bolt d (shown as headed) is extended through the head or part a' of the fixed member and through the slot b' of the movable member b and finally through a clamping member c , which has upon its inner faces grooves c^2 to fit the ribs b^2 and preferably correspondingly tapering, a nut c^3 on the bolt retaining the clamping member thereon and in engagement with the member b .

One or more lugs c' on the inner face of the clamp member extend into the slot b' , preventing displacement of the said member when loosened and also serving to position it properly when tightened.

By means of the lug or shelf a^2 the bolt is always maintained in proper position, whether

the clamp is tight or loose, and no attention has to be paid to the correct positioning of the bolt, so that the final tightening of the clamp cannot throw the standard out of desired adjustment.

From the taper of the wedge it will be seen that the greater the upward pressure put upon the desk or other article the tighter the clamp will hold, and the latter must be loosened to raise the desk.

To prevent depression of the desk or movement opposite the direction of taper of the wedge-shaped member, the member *a* is provided with a series of teeth *a*⁴, shown as adjacent one of the bearings *a*³, to be engaged by a toe or detent *b*⁵ on the movable member *b*.

Preferably the tops of the teeth are substantially horizontal to afford a firm support for said detent toe and member, absolutely preventing depression of said member when clamped and also preventing the movable member from dropping when the clamp is loosened to adjust.

Obviously the ribs could be made on the clamping member to enter grooves in the movable member of the standard, such construction being a mere reversal of that herein shown.

The rib-and-groove construction prevents lateral relative movement of the members of the standard; but it will be obvious that the clamping member could be made to rest directly upon the inclined face of the movable member of the standard, if desired, thus omitting the ribs and grooves, as shown in Fig. 4. In said figure the inclined face of the clamp member *c*¹⁰ rests directly upon the inclined face *b*²⁰ of the movable longitudinally-slotted member *b*¹⁰, the construction otherwise being as heretofore described.

Having fully described my invention, what

I claim, and desire to secure by Letters Patent, is—

1. An adjustable support or standard for furniture, comprising a lower member adapted to be rigidly secured to the floor, a movable member adapted to be secured to the article of furniture and sliding on the fixed lower member, the adjacent faces of said members being parallel to the direction of adjustment of the furniture, a clamping device between which and the member of the standard to which it is attached the other member is locked, said latter member being wedge-shaped, and means to prevent movement of the said member opposite to the direction of taper of the wedge, substantially as described.

2. An adjustable support or standard for furniture, comprising a lower member adapted to be rigidly secured to the floor, a movable member adapted to be secured to the article of furniture and sliding on the fixed lower member, the adjacent faces of said members being parallel to the direction of adjustment of the furniture, a clamping device between which and the member of the standard to which it is attached the other member is locked, said latter member being wedge-shaped and having a toe or projection thereon, and a vertical series of teeth formed on the fixed member, engagement of the toe with a tooth preventing displacement of the movable member opposite to the direction of taper of its wedge, substantially as described.

In testimony whereof I have signed my name to this specification in the presence of two subscribing witnesses.

GABRIEL A. BOBRICK.
